UNITED STATES PATENT OFFICE.

WILLIAM H. PALMER, JR., OF NORWICH, ASSIGNOR TO PALMER BROTHERS,
OF NEW LONDON, CONNECTICUT.

PROCESS OF PREPARING BED-QUILTS FOR SEWING.

SPECIFICATION forming part of Letters Patent No. 413,811, dated October 29, 1889.

Application filed April 29, 1889. Serial No. 308,933. (No specimens.)

To all whom it may concern:

Be it known that I, WILLIAM H. PALMER, Jr., of Norwich, in the county of New London and State of Connecticut, have invented a certain new and useful Improvement in the Process of Preparing Bed-Quilts for Sewing, of which the following is a specification.

My improvement relates to processes for preparing bed-quilts for sewing across their ends.

I will describe in detail a process embodying my improvement, together with certain mechanism by which the same may be conveniently carried out, and then point out the novel features in a claim.

In the accompanying drawings, Figure 1 is a plan or top view of a machine whereby my improvement may be carried out. Fig. 2 is a side elevation of the same. Fig. 3 is a side elevation of a portion of a certain clamp which may be employed. Fig. 4 is an end view of the same. Fig. 5 is a side elevation of another portion of the clamp, and Fig. 6 is an end view of the same. Figs. 3 and 5 are broken away in order to save space, but the portions broken away are like those shown.

The materials of which the bed-quilts are composed comprise the filling material *a*, which may be cotton-batting or any other suitable material interposed between outer coverings *a'* of any woven fabric. The materials thus united are conveyed along in a continuous strip, and their outer edges are sewed together by sewing-machines in a well-known manner. After being thus sewed together the strip is passed between feeding-rollers *a²*. In the machine which I have illustrated for carrying out my process these feed-rollers are mounted in a frame *A*, which frame has a depressed portion *a³*, constituting a receptacle, into which the goods after passing between the feed-rollers are received. In front of the frame *A* is a table *A'*.

In carrying out my process I measure off a definite length of the goods, or sufficient thereof to make a bed-quilt. The goods having been thus measured off, I compress them widthwise and at right angles to the direction of their lengths. Such compression is exerted upon both sides of the goods and

extends wholly across the same, and is exerted in two parallel lines which are adjacent to each other, but have a space between them. The goods are then cut between the lines of compression. The compression is maintained upon both ends of the quilt thus severed, and the same is then in proper condition to be sewed across its ends.

In the machine which I have illustrated as being adapted to carry out my improvement the compression of the goods is accomplished by means of clamps *B* *B'*. These clamps comprise, as here shown, upper bars *b* and lower bars *b'*. The upper bars *b* are provided upon their upper sides at their end portions with springs *b²*, to the outer ends of which are hung links *b³*. The ends of the portions *b'* of the clamps are provided with projections *b⁴*. The frame *A* is transversely recessed at *c*. The lower portions *b'* of the clamps are placed in said recesses. The upper portions *b* are then placed upon the material and the links *b³* are brought down and hooked over the projections *b⁴* at both ends. It will thus be seen that the goods are compressed upon both sides in parallel lines extending at right angles to the direction of length of the goods, and that there is a space between the lines of compression. A knife drawn through this space will sever the measured-off portion of the goods from the balance. The clamps are permitted to remain upon the ends of the severed quilt, so that the compression at these points will be maintained until the sewing across the ends of the quilt is to be performed. The quilt having been severed and conveyed away, the clamp *B'* upon the ends of the strip of goods is moved along until it will fall into a depression *d* in the table *A'*. The required length of material for a quilt is thus measured off and the goods at the required point are again compressed in order to be severed.

What I claim as my invention, and desire to secure by Letters Patent, is—

The process of preparing bed-quilts, consisting in first sewing the material of which the bed-quilt is to be composed along its side edges, then measuring off a sufficient quantity of such material for a quilt, then where

the quilt is to be cut off compressing the material upon both sides throughout its width in parallel lines extending at right angles to the length of the goods, so that a space will 5 be left between said compressions, and subsequently severing the goods between said compressions, whereby both the ends of the quilt so severed and the end of the material

remaining will be maintained under compression after severing, substantially as specified. 10
